GARMENT HANGER

Aloysius G. Ratermann, St. Louis, Mo.

Application May 17, 1935, Serial No. 21,990

7 Claims. (Cl. 223—88)

This invention relates to garment hangers, particularly hangers for coats and trousers. The invention has for its principal object to provide a hanger that will properly support the trousers in an upright position. Other objects are to provide for simplicity and cheapness of construction and to permit the trousers to be quickly and easily mounted on and dismounted from the hanger. The invention consists in the garment hanger and in the construction, combinations and arrangements of parts hereinafter described and claimed.

In the accompanying drawing, which forms part of this specification and wherein like symbols refer to like parts wherever they occur,

Fig. 1 is a side elevation of a garment hanger embodying my invention, showing in dotted lines a pair of trousers suspended therefrom,

Fig. 2 is an enlarged fragmentary view of the end of the hanger having the pivoted trousers supporting member,

Fig. 3 is a vertical cross-section on the line 3—3 in Fig. 1,

Fig. 4 is a cross-section on the line 4—4 in Fig. 1,

Fig. 5 is a horizontal section on the line 5—5 in Fig. 1; and

Fig. 6 is a view similar to Fig. 1 illustrating a modified form of garment hanger.

In the accompanying drawing, my invention is shown embodied in a combination coat and trousers hanger, comprising a single piece of wire that is bent into a triangular frame or main body portion including a bottom bar 1 and upwardly converging coat supporting top bars 2 and 2a twisted together at their upper ends with one of such ends extending above the frame and formed into a hook 3. According to the present invention, the trousers 4 are suspended from the above hanger by means of supporting members 5 and 6 located at the respective lower corners of said hanger.

The trousers supporting member 5 preferably comprises a piece of wire bent into substantially inverted V-shaped form with its closed upper end supported in an opening provided therefor in a clip 7 that is welded or otherwise fixed to the sloping top bar 2 of the hanger. The two branches of the inverted V-shaped member 5 extend downwardly on opposite sides of the bottom bar 1 through openings provided therefor in a cross-member 8 rigidly secured to said bottom bar and are bent toward the adjacent end of the hanger to form hooks 9.

The trousers supporting member 6 is also made

of wire bent into substantially inverted V-shaped form with its closed end pivotally supported in an opening provided therefor in a member 10 fixed to the inclined top bar 2a of the hanger. The branches of this supporting member extend downwardly on opposite sides of the bottom bar 1 through elongated openings 11a provided therefor in a member 11 slidably mounted on said bottom bar. The lower end portions of said branches are bent towards the adjacent end of the hanger 10 frame to form hooks 12 below the bottom bar 1. Sleeved on the bottom bar with one end fixed to the pivoted trousers supporting member 6 and the other end fixed to a member 13 fixed to said bottom bar near the adjacent corner of the hanger 15 is a tension spring 14 that tends to swing the pivoted trousers supporting member away from the fixed trousers supporting member 5.

In the use of the above described garment hanger, the trousers 4 are folded to preserve the 20 creases in the front and rear of the legs and to bring two belt straps 15 opposite each other near the front of the trousers and two belt straps 16 opposite each other near the rear of said trousers. The hooked lower ends 12 of the pivoted supporting member 6 at one corner of the hanger are engaged with the two front belt straps 15; and the two hooked lower ends 9 of the stationary supporting member 5 and the other corner of said hanger are hooked in the two rear 25 belt straps 16, thereby suspending the trousers from the hanger in an upright position. As shown in the drawing, the supporting member 6 for the front of the trousers is made longer than the rear supporting member so as to allow for 30 the dip in the waist line of the trousers and thus make them hang perfectly straight; and the pull of the tension spring 13 on the pivoted supporting member 6 tends to draw the trousers taut at the 35 waist line despite slight differences in waist measurements.

In the modified hanger construction shown in Fig. 6, the hooked trousers supporting members 17 are pivoted to the top bars of the hanger close to the corners thereof and extend downwardly 45 through members 18 slidably on the bottom bar of the hanger. In this construction, a helical compression spring 19 is sleeved on the bottom bar 1 between the two pivoted supporting members 17, with its middle portion fixed to said 50 bottom bar and with its ends bearing against the slide members 18 so as to yieldably hold them against stops 20 provided therefor on said bottom bar. With this construction of hanger, the two supporting members 17 are swung away from 55

each other by the spring 19 therebetween and thus tend to draw the waist band of the trousers taut. This construction locates the supporting members close to the ends of the hanger and is thus adapted 5 to accommodate trousers having relatively large waist measurements.

The invention is not restricted to the type of wire garment hanger shown; and it may be embodied in a skirt hanger as well as in a trousers hanger. 10

What I claim is:

1. A garment hanger comprising a main supporting frame including a bottom rod and members depending from said rod adjacent to the ends thereof and terminating at their lower ends in oppositely disposed outwardly directed garment supporting hooks, means for pivotally securing one of said members for swinging movement on said frame towards and away from the other of 15 said members, and a spring mounted on said frame and cooperating with said pivoted member for swinging it away from said other member.

2. A garment hanger comprising a main supporting frame including a bottom rod and members depending from said rod adjacent to the ends thereof and terminating at their lower ends in oppositely disposed outwardly directed garment supporting hooks, means for pivotally securing one of said members for swinging movement on 20 said frame towards and away from the other of said members, and a tension spring mounted on said rod and cooperating with said pivoted member for swinging it away from said other member.

3. A garment hanger comprising a main supporting frame including a bottom rod and members depending from said rod adjacent to the ends thereof and terminating at their lower ends in oppositely disposed outwardly directed garment supporting hooks, means for pivotally securing one of said members for swinging movement on 25 said frame towards and away from the other of said members, and a compression spring mounted on said rod and cooperating with said pivoted member for swinging it away from said other member.

4. A garment hanger comprising a triangular main frame including a horizontal bottom rod and members depending from said rod adjacent to the ends thereof and terminating at their lower 30

ends in oppositely disposed outwardly directed hooks, said members being pivotally supported on said frame for swinging movement longitudinally of the bottom rod thereof, said rod having stops thereon for limiting the outward swinging movement of said members, and a helical compression spring mounted on said rod for yieldably holding said members against said stops. 5

5. A garment hanger comprising a wire frame bent to form a bottom rod and two upwardly converging top rods, a member fixed to one of said top rods and to said bottom rod and terminating therebelow in an outwardly directed hook, a member pivoted to the other top rod and terminating below said bottom rod in an outwardly directed 15 hook, and a spring mounted on said bottom rod for swinging said pivoted member away from said fixed member.

6. A garment hanger comprising a wire frame bent to form a bottom rod and two upwardly converging top rods, a member fixed to one of said top rods and to said bottom rod and terminating therebelow in a pair of outwardly directed hooks, a member slidably on said bottom rod, a member pivoted to the other top rod and extending downwardly through said slidable member and terminating therebelow in a pair of outwardly directed 20 hooks, and a helical spring sleeved on said bottom rod and cooperating with said slidable member for swinging said pivoted member away from 25 said fixed member.

7. A garment hanger comprising a wire frame bent to form a bottom rod and two upwardly converging top rods, a member fixed to one of said top rods and to said bottom rod and terminating 30 therebelow in a pair of outwardly directed hooks, a member slidable on said bottom rod, a member pivoted to the other top rod and extending downwardly through openings provided therefor in said 35 slidable member and terminating therebelow in a pair of outwardly directed hooks, and a helical spring sleeved on said bar and cooperating with said slidable member for swinging said pivoted member away from said fixed member, the hooks at the lower end of said pivoted member extending 40 below the hooks at the lower end of said fixed member. 45
